UNITED STATES PATENT OFFICE

130,056

DESIGN FOR A COMBINATION SPOON AND BOTTLE CAP REMOVER

Alice Burton, St. Louis, Mo.

Application April 16, 1941, Serial No. 100,415

Term of patent 14 years

To all whom it may concern:

Be it known that I, Alice Burton, a citizen of the United States, residing at St. Louis, in the State of Missouri, have invented a new, original, and ornamental Design for a Combination Spoon and Bottle Cap Remover, of which the following is a specification, reference being had to the accompanying drawing, forming a part thereof, and wherein

Figure 1 is a plan view of a combination spoon and bottle cap remover showing my new design; Figure 2 is a left side elevational view thereof.

I claim:

The ornamental design for a combination spoon and bottle cap remover, as shown.

ALICE BURTON.
